UNITED STATES PATENT OFFICE.

WILLIAM G. BETZ, OF HAMMOND, INDIANA, ASSIGNOR TO STRAUBE PIANO COMPANY,
OF HAMMOND, INDIANA, A CORPORATION OF INDIANA.

PIANO-ACTION.

1,389,290.

Specification of Letters Patent. Patented Aug. 30, 1921.

Application filed April 15, 1918. Serial No. 228,631.

To all whom it may concern:

Be it known that I, WILLIAM G. BETZ, a citizen of the United States, residing at Hammond, in the county of Lake and State 5 of Indiana, have invented a certain new and useful Improvement in Piano-Actions, of which the following is a full, clear, concise, and exact description, reference being had to the accompanying drawings, forming a 10 part of this specification.

My invention relates to piano actions and has to do more particularly with improvements for combination manual and automatic players, an object being to provide 15 improved means for controlling the action by manual and automatic operating means.

In my improved mechanism, when the pneumatic is actuated a comparatively long movement thereof is permitted and further- 20 more the abstract remains stationary, as does also the key, although there is a permanent pivotal connection extending from the abstract to the wippen. Thus separate locking means for the keys is unnecessary.

25 This is brought about by the provision of a so-called double action or intermediate lever which is raised either by the key or pneumatic to operate the action-hammer. Other features of my invention will be more particularly pointed out in the ensuing part of 30 the specification and appended claims.

The present application concerns itself more particularly with improvements over my Patent No. 922,247 for pianissimo de- 35 vises.

Referring now to the accompanying drawings which illustrate the preferred forms of my invention—

Figure 1 is a vertical section through the 40 upper portion of an upright piano with the parts in their normal or unoperated position;

Fig. 2 shows the parts of Fig. 1 but with the key depressed;

45 Fig. 3 is the same as Fig. 1 but with the pneumatic or bellows collapsed and showing the key in its normal or unoperated position;

Fig. 4 is an enlarged view, practically full size, showing a modified form;

50 Fig. 5 is a slightly reduced view of another modified form of my invention; and

Fig. 6 is a detail view of the abstract of Fig. 5.

Referring now more in detail to my in- 55 vention it comprises the usual key-bed 10

carrying a balance rail 11 which pivotally supports the keys 12, these keys being guided at their front end by pins 13 over which a resilient stop 14 is placed preferably in the form of a felt washer. A plurality of 60 paper washers 15 are placed in position in order to give the proper adjustment to the key 12. The rear end of the key is connected through a capstan 16 with a striker or abstract 17 which is supported against trans- 65 verse displacement by a connector 18 extending to the rail 19. The abstract 17 is connected to an intermediate or double-action link 20 at the pivot 21, these parts 17 and 20 also coöperating through a cushioned 70 shoulder or stop 22 through which the intermediate lever 20 is directly raised when the abstract 17 is moved by the key.

This intermediate lever 20 is also operable by a pneumatic or bellows 23 which is 75 controlled from the wind chest and tracker bar in the usual manner. The pneumatic 23 carries an adjustable stud 24, which acts upon a cushioned adjustable stop 25 carried by the intermediate lever 20. Thus this 80 lever 20, which might be termed a double-action lever, may be operated upon either by the key 12 through the abstract 17 for manual playing, or by the pneumatic 23 for automatic playing, each movement being independent of the other. That is, when the abstract 17 is raised by the key 12 the intermediate lever moves directly upward to operate the action without affecting the pneumatic 23 and when said pneumatic is col- 85 lapsed it elevates the free end of the double action lever 20 which pivots at 21 and operates the action without lifting the abstract 17, the pressure thus exerted upon the intermediate lever 20 being effective to maintain 90 the abstract and key 12 in their normal position. Thus it is unnecessary to provide a key stop under the keys for use when automatic playing is desired, the keys and abstracts being automatically maintained in 95 their normal or unoperated position.

Thus it is unnecessary to provide a key stop under the keys for use when automatic playing is desired, the keys and abstracts being automatically maintained in 100 their normal or unoperated position. When the intermediate or double acting lever 20 is operated by the collapse of the bellows 23 as indicated in Fig. 3, the operation is limited by the cushioned adjustable stop 27 105 which is engaged by the resilient or yielding end of lever 20. Thus by the interposition of this yielding stop, a more resilient action is produced. This stop 27 does not come into play when the key is manually de- 110

pressed as indicated in Fig. 2, but at that time the stop 14 under the forward end of the key is effective.

- In certain parts of the action including 5 the wippen, the movement is within certain prescribed limits and of course this is also true of the key and abstract. Also the space between the action and front of the piano for the placing of the pneumatics is limited.
- 10 By means of my improved construction, a long stroke pneumatic may be used, the centers between the pivots of the double-action lever being spaced accordingly. Thus a narrow pneumatic may be used and also it 15 may be set back from the front of the piano and farther beneath the wippen. I am thus enabled to secure the long stroke which is desirable, without the sacrifice of transverse space.
- 20 The action above the abstract 17 and double action lever 20 as connected to the wippen 26 may be of the usual construction, that shown being of a known make and including the usual action rail 26^a pivotally 25 supporting the wippen 26. A jack 27^a is pivotally supported upon the wippen 26 so as to be practically directly above the abstract 17 so that the upward pressure is on practically a straight line. The jack 27^a 30 engages the leather faced hammer butt 28, the stop extension on the jack 27 being adapted to engage the jack stop 29 when the jack is raised, whereby the continued upward movement of the jack causes it to free 35 itself from the hammer butt as indicated in Figs. 2 and 3 so that the hammer is free to strike the string and rebound. The usual damper rod 30 is also provided being operated in a well-known manner by the extension 40 of the wippen 26. However, as already referred to, this upper portion of the action mechanism may vary.

In Figs. 5 and 6 is shown a modified form of my invention in which the abstract 17 45 instead of being made of one piece as shown in the other figures, has its rearwardly extending arm 17^a preferably made of a separate piece and secured to the shank of the abstract which carries at its upper end the 50 cushioned shoulder corresponding to the stop 22 already described. By means of this construction it is possible to lengthen the fulcrum on the intermediate lever 20 and without requiring a broad wood blank for 55 the abstract 17 as in the case of Figs. 1 to 4. Also in the form shown in Fig. 5 I provide a double action lever 20 having a slightly different yielding stop 20^a, this end 20^a being slotted almost back to the screw 25 so as to 60 provide the greatest length to the stop end 20^a. This lever 20 is also thinned at 20^b, so as to produce further resiliency.

It will be apparent that by means of my improved construction it is possible to get 65 the proper stroke of the wippen 26 and also

a long stroke of the bellows without unduly extending the wippen toward the front of the piano. This is because of the interposition of the double action lever 20 which permits of any desired stroke of the bellows by 70 simply using the proper pivotal centers. At the same time the bellows may be moved back from the front of the piano. This is important in view of the small amount of space at this point. Furthermore, by my 75 improved construction, the automatic and manual mechanism may each have its own stop, the automatic mechanism when actuated being stopped by the resilient arm at the end of the intermediate lever 20 while 80 the manual mechanism, when actuated, is stopped by the yielding washer under the forwarded end of the key. Thus there is independent regulation of the stroke or movement of the hammer mechanism for 85 both manual and automatic playing and there is no interference between the stops. Also when the keys are pneumatically operated it is unnecessary to provide any lock therefor as the pressure upon the abstract 17 90 automatically maintains the abstract and key in their normal position thereby preventing any undue actuation thereof.

Another important feature is that there is no stop on the wippen and the stops are so 95 placed that there is no substantial pressure on any of the pivot bearings of the action when the stops come into play. Also the pneumatic stop, it will be noted, is such that the manual operation is not affected in any 100 way when the piano is manually played; the operation is the same as though no automatic player were there.

For the purpose of illustrating my invention I have shown several preferred forms 105 thereof, but I understand that changes and modifications will readily occur to those skilled in the art and therefore I do not desire to be limited to the exact structures shown and described, but aim to cover all 110 that which comes within the spirit and scope of the appended claims.

What I claim as new and desire to secure by Letters Patent is:

1. A piano action including an abstract 115 having at its upper end a rearwardly and upwardly extending arm provided with a wippen operating shoulder at the upper end of the abstract, a wippen, an action lever intermediately pivoted to the wippen, and 120 abstract and pneumatic connections to opposite ends of the action lever.

2. A piano action including an abstract having at its upper end a rearwardly and upwardly extending arm so as to leave a 125 shoulder at the upper end of the abstract, a wippen, an action lever intermediately pivoted to the wippen, and connected at its rear end to abstract arm so as to bring it above the shoulder for direct operation when the 130

abstract is operated, and a pneumatic connection to the front end of the intermediate lever for operating the wippen independent of the abstract.

5 3. A piano action including an abstract having at its upper end a rearwardly and upwardly extending arm so as to leave a shoulder at the upper end of the abstract, a wippen, an action lever intermediately pivoted to the wippen and connected at its rear end to abstract arm so as to bring it above the shoulder for direct operation when the abstract is operated, and a pneumatic connection to the front end of the intermediate lever for operating the wippen independent 10 of the abstract, and yielding stops respectively effective when the pneumatic or the abstract is used, one of said stops being independently effective when the pneumatic is used and the other when the abstract is used.

15 4. A piano action including an abstract, a wippen, an intermediate lever pivotally connected to the wippen and to the abstract, and a pneumatic operating upon a point of the intermediate lever to permit greater movement of the pneumatic than of the wippen.

20 5. A piano action including an abstract, a wippen, an intermediate lever pivotally connected to the wippen and to the abstract, and a pneumatic operating upon a point of the intermediate lever to permit greater movement of the pneumatic than of the wippen, and a direct connection between the abstract and lever for moving the lever independent 25 of the pneumatic.

30 6. A piano action including an abstract, a key abutting the lower end of the abstract, a wippen, a pneumatic, and connections between the abstract and wippen effective for 35 operating the wippen by the pneumatic and forcibly maintaining the abstract and key in their normal position.

40 7. A piano action including a wippen, an abstract, a pneumatically operated intermediate lever, pivotally connected to the abstract and to the wippen for operating the

action, and a stop extension directly on the intermediate lever for limiting the movement of the action. 50

8. A piano action including a wippen, an abstract, a pneumatically operated intermediate lever pivotally connected to the abstract and to the wippen for operating the action, and a resilient stop extension directly 55 on the intermediate lever for limiting the movement of the intermediate lever.

9. A piano action including an abstract having its upper end provided with a shoulder and with a rearwardly extending part, a wippen, an action lever intermediately pivoted to the wippen, and abstract and pneumatic connections to opposite ends of the action lever. 60

10. A piano action including an abstract having its upper end provided with a shoulder and with a rearwardly extending part, a wippen, an action lever intermediately pivoted to the wippen, and connected at its rear end to the abstract arm so as to bring it 70 above the shoulder for direct operation when the abstract is operated, and a pneumatic connection to the front end of the intermediate lever for operating the wippen independent 75 of the abstract.

11. A piano action including an abstract having its upper end provided with a shoulder and with a rearwardly extending part, a wippen, an action lever intermediately pivoted to the wippen and connected at its 80 rear end to the abstract arm so as to bring it above the shoulder for direct operation when the abstract is operated, and a pneumatic connection to the front end of the intermediate lever for operating the wippen independent 85 of the abstract, and yielding stops respectively effective when the pneumatic or the abstract is used, one of said stops being independently effective when the pneumatic is used and the other when the abstract is used. 90

In witness whereof, I hereunto subscribe my name this 9th day of April, A. D. 1918.

WILLIAM G. BETZ.
